UNITED STATES PATENT OFFICE.

JAMES M. TRINER, OF CHICAGO, ILLINOIS, ASSIGNOR TO THE PELOUZE SCALE AND MANUFACTURING COMPANY, OF SAME PLACE.

DESIGN FOR A BLANK FOR SCALE-FRAMES.

SPECIFICATION forming part of Design No. 29,889, dated December 27, 1898.

Application filed October 31, 1898. Serial No. 695,136. Term of patent 14 years.

To all whom it may concern:

Be it known that I, JAMES M. TRINER, a citizen of the United States, residing at Chicago, in the county of Cook and State of Illinois, have invented and produced a new and original Design or Useful Shape for a Blank for Scale-Frames, of which the following, in connection with the accompanying drawing, is a full, clear, and exact specification.

The said drawing is a plan or pattern of a blank for scale-frames embodying my design.

The leading feature of my design consists of a four-sided blank having the offset or notch A in one side thereof.

The main or body portion B of the blank is in general outline rectangular and oblong, and at an intermediate point in one of its long sides is formed the offset A, whose inner edge is substantially parallel with the opposite edge of the blank; but the ends or shoulders C of the offset or notch are slightly

rounded off into the general outline of the body portion. Each of the ends of the blank is also provided with an offset or elongated cut-out D, and each of the upper corners just 25 above the cut-outs D is provided with a nib or ear E and just below the cut-outs D with a similar ear or nib F. Near each of the lower corners and on the long side of the blank is formed a nib or ear G, and between 30 these and near the mid-length are formed two pairs of such nibs H I.

Having thus described my invention, what I claim as new therein, and desire to secure by Letters Patent, is—

The design for a blank for scale-frames substantially as herein shown and described.

JAMES M. TRINER.
